5 Claims. (Cl. 73—37.5)

This invention relates to extensometers.

A known extensometer has a chamber with an inlet containing a restriction through which air at a constant supply pressure is passed. A pressure gauge is connected to the chamber, and the chamber also has an outlet orifice into which extends a tapered needle valve connected to the specimen under test. Movement of the needle valve consequent upon a dimensional change of the test specimen varies the effective area of the outlet orifice and hence the air pressure inside the chamber. In this way the pressure recorded by the gauge can be related to the dimensional change of the test specimen.

An extensometer according to the invention comprises a sleeve member having a signal port intermediate inlet and outlet ports, and a slide member so disposed within the sleeve member that between them is defined a restriction to flow of fluid from the inlet port to the outlet port which is of uniform section over at least such portion of the slide member as intervenes between the inlet port and the signal port, whereby relative longitudinal movement between the members by movement transmitted to one of the members by a dimensional change of a test specimen varies the length of the restriction through which the fluid flows before reaching the signal port. With pressurised fluid at a constant supply pressure fed to the inlet port the fluid pressure at the signal port is found to bear a substantially linear relationship to the length of the restriction traversed by the fluid in reaching the signal port and consequently to the dimensional change of the test specimen.

By way of example an extensometer in accordance with the invention will now be described with reference to the accompanying drawings which shows a longitudinal view (partly in section) of an extensometer, together with associated equipment which is illustrated diagrammatically.

In the drawing an extensometer 1 comprises a sleeve member 2 of circular section having at one end thereof a pressurised fluid inlet port 3, at the other end thereof an outlet port 4, and intermediate the ends a fluid-pressure signal port 5, and a cylindrical slide member 6 disposed within the member 2, the members 2, 6 defining between them a restriction 7 (shown enlarged for clarity) of uniform section over the length of the member 6.

The inlet port 3 is formed in an end wall 3a of the sleeve member 2 and has a connecting pipe 8, and the signal port 5 is formed by a hood 9 extending circumferentially round and sealed to the outer wall of the member 2 and a plurality of circumferentially equi-spaced passages 10 extending from a circumferential groove 11 formed in the inner wall of the member 2 to the interior of the hood 9. The port 5 has a connecting pipe 12. The slide member 6 has an intermediate portion 6a between end portions 13, 14 of reduced diameter, the end portions 13, 14 each having three circumferentially equi-spaced locating pins 15 (one of which is shown for each of the end portions 13, 14). One of the pins 15 on the end portion 13 (and correspondingly on the end portion 14) is lightly spring-loaded, the others being rigidly secured. The pins 15 serve to locate the slide member 6 substantially centrally in the sleeve member

2, the inner surface of the sleeve member 2 and the surface of the portion 6a of the slide member 6 being honed so as to be of a size and finish such that the restriction 7 is in the form of a narrow clearance between the members 2, 6 and of uniform annular section over the length of the portion 6a of the slide member 6. Typically the restriction 7 has a radial width of one thousandth of an inch for a diameter of the portion 6a of the slide member 6 of half an inch. The spring-loaded pins 15 serve to maintain a constant relative radial location between the members 2, 6 over the whole operative travel of the member 6. The portion 14 has secured to it a coaxial feeler rod 16 extending beyond the port 4. A source 18 of pressurised gas is connected to the pipe 8 by way of a constant pressure valve 19, a pressure gauge 20 being provided. A pressure gauge 21 is connected to the end of the pipe 12 remote from the port 5.

In use the sleeve member 2 is mounted so as to be held stationary and pressurised gas from the source 18 is fed through the valve 19 and pipe 8 to the port 3 at a constant supply pressure to flow through the restriction 7 to the port 4. A dimensional change of a test specimen 17 causes longitudinal movement of the slide member 6 by transmission through the feeler rod 16 (which constitutes means for causing relative longitudinal movement between the members 2, 6) and thus varies the length of the restriction 7 through which the gas flows before reaching the signal port 5. The pressure recorded on the gauge 21 is found to bear a substantially linear relationship to the length of the restriction 7 traversed by the gas in reaching the signal port 5 and consequently to the dimensional change of the test specimen 17, since the uniform section of the restriction 7 over its length ensures that the restriction of gas flow per unit length is constant.

The extensometer 1 has greater accuracy over a wider range (typically an accuracy of 0.1 to 0.2% over a range of movement of one inch) than the known extensometer referred to above.

The invention is not limited to the details of the example described above. Thus the member 6 may be held stationary using a support extending through the port 4 (the rod 16 being dispensed with) and a dimensional change of the test specimen transmitted through another feeler rod to cause longitudinal movement of the sleeve member 2. Such an arrangement requires the pipes 8, 12 to be flexible, and for this reason the arrangement in which the member 6 is movable is preferred.

The invention has particular application in high temperature environments in that the simple form of the sleeve and slide members facilitates any compensation which may be necessary at elevated temperatures.

I claim:

1. An extensometer comprising a sleeve member having a signal port intermediate an inlet port and an outlet port, a slide member disposed within the sleeve member, the slide member having an intermediate portion between end portions of reduced size located with respect to the sleeve member, and the intermediate portion defining with the sleeve member an annular restriction to flow of fluid from the inlet port to the outlet port, the restriction being of uniform section over the length of the intermediate portion, and means for causing relative longitudinal movement between the members consequent upon a dimensional change of a test specimen thereby varying the length of the restriction through which the fluid flows before reaching the signal port.

2. An extensometer as claimed in claim 1, wherein said means comprises a feeler rod secured to one of said end portions and extending beyond said outlet port.

3. An extensometer comprising a sleeve member having at one end an inlet port and at the other end an outlet port, the sleeve member also having a signal port intermediate the inlet and outlet ports, a slide member disposed longitudinally within the sleeve member, the slide member having an intermediate portion between end portions of reduced size, the end portions being disposed one to each side of said signal port and located with respect to the sleeve member, and the intermediate portion defining with the sleeve member an annular restriction to flow of gas from the inlet port to the outlet port, the restriction being of uniform section over the length of the intermediate portion, a feeler rod coaxial with the slide member, the rod being secured to one of said end portions and extending beyond said outlet port for causing longitudinal movement of the slide member relative to the sleeve member consequent upon a dimensional change of a test specimen to vary the length of the restriction through which the gas flows before reaching

the signal port, means for feeding pressurised gas at constant pressure to the inlet port and means for measuring the gas pressure at the signal port.

4. An extensometer as claimed in claim 1, wherein each end portion has pin means for locating the slide member radially with respect to the sleeve member.

5. An extensometer as claimed in claim 1, wherein the annular restriction has a radial width of one thousandth of an inch for a diameter of the intermediate portion of one half inch.
